UNITED STATES PATENT OFFICE.

NATHAN A. BUCKINGHAM, OF JACKSONVILLE, ILLINOIS.

SASH-FASTENER.

SPECIFICATION forming part of Letters Patent No. 425,021, dated April 8, 1890.

Application filed February 10, 1890. Serial No. 339,855. (No model.)

To all whom it may concern:

Be it known that I, NATHAN A. BUCKINGHAM, a citizen of the United States, residing at Jacksonville, in the county of Morgan and State of Illinois, have invented certain new and useful Improvements in Sash-Holders, of which the following is a specification.

My present invention has special reference to that class of sash-holders which are used at the sides of the sashes to hold them snugly in the window-frame to prevent their rattling, and which are so constructed as to hold the sash firmly at any height to which it may be adjusted.

15 The invention consists in a certain novel construction, as will be hereinafter first fully described, and then pointed out in the claims.

In the accompanying drawings, which fully illustrate my invention, Figure 1 is a perspective view of a portion of a window, showing my improved device in position thereon. Fig. 2 is a plan view of the upper edge of the sash; and Fig. 3 is a vertical section of a portion of the window, showing the holder in 25 elevation.

Referring to the drawings particularly by letter, A designates the lower sash, B the upper sash, and C the parting-strip, all of the usual or any preferred construction.

30 In practice I will employ a locking device at the center of the sashes to draw them toward each other and hold them together; but such device forms no part of the present invention, as it may be of any desired construction and does not affect and is not affected by the operation or construction of the improvements forming the subject-matter of this application.

In order that my invention may be more 40 readily comprehended and appreciated, I have illustrated a spring-bolt on the lower sash engaging a keeper-plate on the upper sash; but a cam-lever engaging a pin might be used or any other similar arrangement employed.

45 The parting-strip has secured to its opposite sides the keeper-plates D D, which are provided on their outer sides with the horizontal grooves or corrugations E, as shown. These keeper-plates may extend the entire 50 length of the sashes; but for ordinary purposes such lengthy plates are not necessary.

On the upper edge of the lower sash and on the lower edge of the upper sash I secure, at the sides of the same, the locking-plates F F, which may be of any desired size, according to the size and weight of the sash, and may also be of any preferred configuration, provided certain features to be now specified are preserved. On the inner edges of the locking-plates, at the outer ends of the same, 55 I provide the lateral extensions G, which project beyond the edge of the sash and are adapted to engage the grooves or corrugations in the keeper-plates, as shown. The locking-plates are further provided at their ends with the notches or open-ended slots H, which register with the sash-cord grooves I in the side edges of the sashes, and thus provide for the uninterrupted movement of the sash-cords. This construction also enables me to 60 prolong the locking-plate, so that it will extend inward entirely to the window-frame, and thus obtain a strong hold upon the keeper-plate.

The operation of the device is thought to 75 be obvious from the foregoing description, taken in connection with the accompanying drawings. When the sash is being raised or lowered, the locking-plate slips past the keeper-plate, and thus permits the sash to be readily adjusted to any desired height. After the sash has been brought to the position desired the sashes are forced together, thereby drawing the locking-plate into engagement with the keeper-plate, and thereby locking the sash 80 in its adjusted position, so that it cannot be raised or lowered by burglars or other unwarranted persons, and firmly supporting it against accidental displacement.

My device is very simple in its construction and can be manufactured at a slight cost. It is efficient in its operation, and its advantages are thought to be obvious.

Having thus described my invention, what I claim, and desire to secure by Letters Patent, is—

1. In a sash-holder of the character described, the locking-plate adapted to be secured upon the sash and having a notch in its end registering with the sash-cord groove 100 in the sash, combined with means for drawing the sashes together, as set forth.

2. The combination of the keeper-plate secured to the parting-strip and having a series of grooves in its side, the unyielding locking-plate rigidly secured to the sash and having
5 a lateral projection on its front edge engaging said grooves, and means for drawing the sashes together, as set forth.

In testimony whereof I affix my signature in the presence of two witnesses.

NATHAN A. BUCKINGHAM.
